DETERGENT COMPOSITIONS

Melvin E. Tuvell, Los Angeles, Calif., assignor to Monsanto Chemical Company, St. Louis, Mo., a corporation of Delaware
 No Drawing. Filed July 22, 1957, Ser. No. 673,161
 13 Claims. (Cl. 252—138)

This invention relates to the preparation of improved heavy-duty detergent compositions which are particularly suitable for use in automatic washing machines.

Various heavy-duty detergent compositions have been proposed and introduced into commercial practice. Many of these detergent compositions are built formulations essentially containing a minor amount of a nonionic or anionic surface-active agent; various alkaline metal phosphates such as sodium tripolyphosphate, tetrasodium pyrophosphate, and mixtures thereof; other alkaline materials such as sodium carbonate and sodium bicarbonate; and various soluble alkaline metal silicates as corrosion inhibitors therein. The formulations may also contain other salts such as sodium sulfate, sodium borate, etc., and relatively small amounts of other additives as for example an antisoil redeposition agent such as carboxymethyl cellulose, and dyes, perfumes, etc., as desired.

These prior art detergent formulations have given excellent service particularly as controlled suds formulations for use with automatic washers. However it has subsequently been found that the aforesaid formulations may be found to contain varying amounts of a fine, insoluble, sand-like material which clings to the garments washed with said detergent and presents an objectionable appearance. This insoluble material has been identified as silicon dioxide and has been found present in an amount of up to about 6 percent by weight of commercial detergent compositions and under extreme conditions the insoluble content of the formulation can vary up to about 8 percent. The formation of the insoluble silicon dioxide is caused by the degradation of the soluble silicates employed in the detergent compositions and may become a serious problem where the detergent composition has been subjected to relatively high temperatures during transportation and storage and/or has been held for a long period of time prior to use. For example three widely distributed commercial built detergent compositions when subjected to an elevated temperature for a period of up to 48 hours were found to contain the following percent of insolubles, on a dry basis: I, 3.12; II, 5.72; and III, 6.29. Relatively long standing of the detergent composition in free contact with the air after the container has been opened also has been found to accelerate the formation of the insoluble silicon dioxide.

It is the principal object of this invention to provide improved heavy-duty detergent compositions which are stable for relatively long storage periods and are stable at relatively high temperatures as may be encountered in truck bodies, railroad cars, storage areas, and the like. Another object of this invention is to provide controlled suds detergent compositions which are particularly suitable for use in automatic washing machines. Still

2

another object of this invention is to provide a detergent composition which can be employed in the presence of soft metals and metal alloys, such as aluminum, copper, zinc, brass, bronze, and the like, which are employed in the construction of washing machines, without causing harmful corrosion. Other objects will be apparent from the following disclosure.

It has now been found that built detergent compositions containing soluble silicofluorides and preferably soluble alkaline metal and alkaline earth metal silicofluorides, wherein ammonium is treated as an alkaline metal, in an amount of from about 2 to about 9 weight percent and preferably from about 3 to about 5 weight percent, based on the detergent composition, are characterized by a material improvement in their ability to withstand relatively high temperature and long storage time without the formation of excessive insoluble material. Illustrative built detergent compositions, wherein all parts are parts by weight, are generally defined by the formulation essentially containing:

Item	Material	Parts
25	Nonionic and/or anionic surface active agent.....	5-35
1	Sodium tripolyphosphate, tetrasodium pyrophosphate, potassium tripolyphosphate, tetrapotassium pyrophosphate or mixtures thereof.	20-60
2	Alkaline material from the class consisting of sodium carbonate, sodium bicarbonate, sodium sesquicarbonate, and mixtures thereof.	10-25
30	Soluble alkaline metal and alkaline earth metal silicofluorides.	2-9

35 The improved detergent compositions can also include minor amounts of other materials as desired such as antisoil redeposition agents, optical brighteners, dyes, perfumes, foam stabilizers, and the like.

40 The nonionic surface active agent can be a condensation product of the lower alkylene oxides containing up to 4 carbon atoms, for example, ethylene oxide, propylene oxide, butylene oxide, and mixtures thereof, with a compound, or compounds, having one or more active hydrogen atoms, as for example, aliphatic mercaptans,

45 alkyl phenols, fatty acids, alcohols, amines, and the like, which compounds preferably have a molecular weight of less than about 400. The mole ratio of the alkylene oxide to the active-hydrogen-containing compound is from about 3 to about 20 and preferably from about 9 to about 15. Illustrative nonionic surface active agents are: tertiary dodecyl mercaptan with 10 moles of ethylene oxide, tertiary nonylphenol with 15 moles of ethylene oxide, dodecylphenol with 10 moles of ethylene oxide, tetradecylphenol with 12 moles of ethylene oxide, tall oil fatty acids with 11 moles of ethylene oxide, tall oil fatty acids with 15 moles of ethylene oxide, n-tetradecanol with 10 moles of ethylene oxide, 5-ethylnonanol-2 with 15 moles of ethylene oxide, cocoanut oil alcohols

55 with 10 moles of ethylene oxide, 2-butyloctanol-1 with 10 moles of ethylene oxide, dodecanol with 2 moles of propylene oxide plus 6 moles of ethylene oxide, octadecanol with 18 moles of ethylene oxide, hexadecanol with

4 moles of propylene oxide plus 16 moles of ethylene oxide, hexadecylamine with 4 moles of propylene oxide plus 12 moles of ethylene oxide, and the like.

The anionic surface active agents can be selected from the group comprising the sodium alkyl sulfates, the sodium alkyl sulfonates, the sodium alkylaryl sulfonates, the sodium salts of esters of polyhydric alcohol-sulfonates, the sodium salts of sulfated or sulfonated alkyl amides, the sodium salts of sulfated or sulfonated esters, and the like, such as sodium dodecyl sulfate, sodium dodecyl sulfonate, sodium dodecylbenzene sulfonate, sodium glyceryl monolaurate sulfate, sodium 1-(N,N'-oleyl methyl)aminoethane sulfonate, sodium methyl laurate sulfonate, and the like.

The illustrative detergent compositions containing the selected silicofluoride were found to have substantially equivalent detergents properties and possessed substantially similar favorable characteristics regarding the inhibition of corrosion to soft metals as the similar prior art compositions containing the soluble alkaline metal silicates.

It has also been found that the combination of the silicofluorides with soluble silicates are effective at concentrations appreciably lower than that required to afford protection against the corrosion of soft metals when used alone. Accordingly, the soluble silicofluorides can be advantageously employed to replace the soluble alkali metal silicates of the prior art formulations in whole or in part.

The improved detergent compositions of this invention can be prepared by a dry-mix procedure, or can be formulated as a slurry and subsequently dried by spray drying, drum drying, or other suitable means, or can be employed as a heavy-duty liquid detergent composition.

The following examples are illustrative of the instant invention.

EXAMPLE 1

A detergent composition was formulated containing the following materials in parts by weight.

Formulation A

	Parts
Condensation product of one part of tall oil with 1.6 parts of ethylene oxide	15
Sodium tripolyphosphate	22
Tetrasodium pyrophosphate	22
Sodium carbonate	20
Sodium silicofluoride	5
Water	15
Sodium carboxymethyl cellulose	0.6
Perfume and dye	0.04
	100

Similar formulations were prepared wherein various sodium silicate solutions were substituted for the sodium silicofluoride and water in the aforesaid detergent composition. The sodium silicate (38% solids) had a ratio of $\text{SiO}_2:\text{Na}_2\text{O}$ of 3.2:1 in Formula B, 2.9 in Formula C, and 2.6 in Formula D.

The aforesaid samples were confined in sealed con-

tainers and subjected to a temperature of 70° C. for a period of 20 days. Then the percent of insoluble material in the detergent compositions was determined by the following procedure.

5 A two-gram sample of the detergent composition was weighed out and introduced into 100 ml. of distilled water at about 140° F. while stirring at about 1200 r.p.m. Agitation was continued for a 10-minute period and the contents of the vessel was then transferred to a weighed centrifuge tube and centrifuged for 10 minutes at about 16 G, then the supernatant liquor was poured off and the solid precipitate was washed with distilled water and again centrifuged for 10 minutes. Thereafter 10 the water was poured off and the insoluble residue was dried to constant weight in an oven at 105° C. the determination was run in duplicate for each sample evaluated.

The percent of insolubles, on a dry basis, was found to be as follows:

	Formula	Containing—	Percent Insolubles
25 A	Sodium silicofluoride		1.1
B	Sodium silicate ($\text{SiO}_2:\text{Na}_2\text{O}=3.2$)		7.7
C	Sodium silicate ($\text{SiO}_2:\text{Na}_2\text{O}=2.9$)		7.8
D	Sodium silicate ($\text{SiO}_2:\text{Na}_2\text{O}=2.6$)		7.4

EXAMPLE 2

It was shown that prolonged exposure to the atmosphere was a further major contributing factor to the formation of insoluble "sand" in the prior art detergent formulations. The absorption of carbon dioxide from the atmosphere followed by neutralization of the sodium silicate with the subsequent polymerization and precipitation of silicon dioxide was indicated to be the cause of "sand" formation by this means. Accordingly, to evaluate the detergent compositions by an accelerated exposure test they were subjected to aeration by a relatively high-content carbon dioxide atmosphere.

35 A sample of the detergent composition was placed in a closed system and aerated by passing a mixture of nitrogen-carbon dioxide therethrough for a period of four hours at about 23° C. The gas mixture contained 9.6 percent, by volume, carbon dioxide. Thereafter the percent of insoluble, on a dry basis, was determined as described in Example 1 and found to be as follows:

	Formula	Containing—	Percent Insolubles
40 A	Sodium silicofluoride		0.15
B	Sodium silicate ($\text{SiO}_2:\text{Na}_2\text{O}=3.2$)		4.64
C	Sodium silicate ($\text{SiO}_2:\text{Na}_2\text{O}=2.9$)		5.31

55 The aforesaid examples clearly indicate the material superiority of the detergent compositions of this invention containing a soluble silicofluoride in place of the silicate in whole or in part.

60 Other illustrative detergent compositions which can be employed are for example as shown in the following table, wherein the components are expressed in parts by weight.

Component	Formulations

- a Tall oil fatty acids—11 moles ethylene oxide.
- b Tertiary dodecyl mercaptan—10 moles ethylene oxide.
- c Tertiary tetradecyl mercaptan—20 moles ethylene oxide.
- d Tertiary octylphenol—10 moles ethylene oxide.
- e Tertiary nonylphenol—15 moles ethylene oxide.
- f Tertiary nonylphenol—10 moles ethylene oxide.
- g Tall oil fatty acids—12 moles ethylene oxide.
- h Dodecylphenol—10 moles ethylene oxide.
- i Hexadecanol—4 moles propylene oxide plus 16 moles ethylene oxide.
- j Cocoanut oil alcohol—10 moles ethylene oxide.
- k Tetradecanol—10 moles ethylene oxide.
- l Hexadecylamine—4 moles propylene oxide plus 12 moles ethylene oxide.
- m Mixture 10 parts nonylphenol—10 moles ethylene oxide and 5 parts sodium dodecylbenzene sulfonate.
- n Polypropylene glycol ethylene oxide condensate.
- o Tall oil fatty acids—14 moles ethylene oxide.
- p Sodium dodecylbenzene sulfonate.
- q Sodium octadecyl sulfate.

I claim:

1. A built detergent composition comprising (1) 20 to 60 parts of an alkali metal polyphosphate selected from the group consisting of sodium tripolyphosphate, tetrasodium pyrophosphate, potassium tripolyphosphate, tetrapotassium pyrophosphate, and mixtures thereof; (2) 10 to 25 parts of an alkaline material from the group consisting of sodium carbonate, sodium bicarbonate, sodium sesquicarbonate, and mixtures thereof; (3) 2 to 9 parts of a water-soluble silicofluoride; and (4) 5 to 35 parts of a surface-active agent from the group consisting of anionic and nonionic surface-active agents, and mixtures thereof; wherein all parts are parts by weight; and which detergent composition is characterized by the stability thereof against the formation of a deleterious quantity of insoluble compounds when subjected to storage conditions and elevated temperatures, and by a substantial freedom from corrosion of soft metals.

2. The detergent composition of claim 1, wherein the water-soluble silicofluoride is an alkaline metal silicofluoride.

3. The detergent composition of claim 1, wherein the water-soluble silicofluoride is an alkaline earth metal silicofluoride.

4. The detergent composition of claim 2, wherein the alkaline metal silicofluoride is sodium silicofluoride.

5. The detergent composition of claim 2, wherein the alkaline metal silicofluoride is potassium silicofluoride.

6. The detergent composition of claim 2, wherein the alkaline metal silicofluoride is lithium silicofluoride.

7. The detergent composition of claim 2, wherein the alkaline metal silicofluoride is ammonium silicofluoride.

8. The detergent composition of claim 3, wherein the alkaline earth metal silicofluoride is magnesium silicofluoride.

9. The detergent composition comprising a mixture of the following essential ingredients:

Parts

Sodium tripolyphosphate	22
Tetrasodium pyrophosphate	22
Sodium carbonate	20
Sodium silicofluoride	5

35 Condensation product of one part of tall oil with 1.6 parts of ethylene oxide 15
Water 15

wherein all parts are by weight.

40 10. The detergent composition comprising a mixture of the following essential ingredients:

	Parts
Sodium tripolyphosphate	45
Sodium carbonate	10
Sodium sulfate	25
45 Sodium silicofluoride	5
Condensation product of one mole tetradecanol with 10 moles ethylene oxide	7
Water	8

50 wherein all parts are by weight.

11. The detergent composition comprising a mixture of the following essential ingredients:

	Parts
Sodium tripolyphosphate	25
55 Tetrasodium pyrophosphate	20
Sodium carbonate	10
Sodium sulfate	20
Sodium silicofluoride	5
Condensation product of one mole tertiary nonylphenol with 10 moles ethylene oxide	10
Water	10

wherein all parts are by weight.

12. The detergent composition comprising a mixture of the following essential ingredients:

	Parts
Sodium tripolyphosphate	35
Sodium carbonate	10
Sodium sulfate	10
Sodium silicofluoride	5
Sodium dodecylbenzene sulfonate	35
Water	5

78 wherein all parts are by weight.

13. The detergent composition comprising a mixture of the following essential ingredients:

	Parts		
Sodium tripolyphosphate	45	1,935,663	
Sodium carbonate	10	5	2,174,110
Sodium sulfate	10	2,213,477	
Sodium silicofluoride	5	2,365,215	
Sodium octadecyl sulfate	20	2,594,431	
Water	10		

wherein all parts are by weight.
